UNITED STATES PATENT OFFICE.

ALFRED J. MEYER, OF MILWAUKEE, WISCONSIN.

COMBINED TELEGRAPH RELAY AND SOUNDER.

No. 909,198.

Specification of Letters Patent.

Patented Jan. 12, 1909.

Application filed September 19, 1907. Serial No. 393,642.

To all whom it may concern:

Be it known that I, ALFRED J. MEYER, a citizen of the United States, residing at Milwaukee, county of Milwaukee, and State of Wisconsin, have invented new and useful Improvements in a Combined Telegraph Relay and Sounder; of which the following is a specification.

The object of my invention is to provide a device for increasing the volume of sound produced by the vibratory movement of the armature of a relay instrument of an ordinary telegraph system, whereby a clear distinct sound is produced and the use of a local battery or an ordinary sounder previously used for such purpose is dispensed with.

The construction of my device is explained by reference to the accompanying drawings in which,

Figure 1 is a rear view, and Fig. 2 an end view of an ordinary relay instrument provided with my sound increasing device, the sounding drum being shown in section to disclose the interior construction. Fig. 3 represents a modified form of my sounding apparatus removed from the relay instrument.

Like parts are identified by the same reference characters throughout the several views.

The relay instrument comprising the electro magnets 2, supporting base 3, supporting post 4, adjusting screw 5, clamping nut 6, armature 7, armature actuating spring 8, spring supporting screw 9, clamping nut 10, and adjustable horizontal bar 11 are all substantially of ordinary construction and need not be herein more fully described.

My invention pertains more especially, as previously stated, to the means employed for increasing the volume of sound which is produced by the vibratory movement of the armature consisting in the drum 12 which is rigidly supported above the armature from the upper side of the electro magnets 2. The adjustable contact bearing screws 13, 13, and the armature 14 which extends upwardly from the center of the armature 7 and contact head or hammer 15, which is adapted as the armature vibrates toward and from the electro magnets to be brought in contact with the opposing ends of said adjustable screws 13, when owing to the vibration of the drum the sound produced by such contact is greatly increased.

The drum 12 comprises the annular pe-

riphery 16 and the opposing heads 17, 17. An aperture 18 is formed through the lower side of the drum for the reception of the vibratory arm 14. While the drum thus formed will greatly increase the sound, I preferably employ in connection therewith a sounding horn 18^a, the converging ends of which are inserted through the aperture 20 in the side of the drum, whereby the sound produced within the drum may be thrown in the direction of the operator to whom the message is sent.

While I preferably employ a single arm in connection with a sounding drum and operate the same centrally within such drum as shown in Fig. 1, if desired a bifurcated arm 22 may be substituted therefor. The arm 22 extends upwardly upon the exterior sides of the drum and is provided with adjustable contact bearing screws 24, 24, which are adapted as said armature vibrates, to contact with the heads of the drum upon their exterior surfaces as shown in Fig. 3, the other parts of the device are made substantially as shown in Figs. 1 and 2. It will be understood that the stroke of the vibratory arm may be increased, if desired, by turning back the contact bearing screws or diminished by turning such screws in the opposite direction whereby the sound of the stroke will be increased or diminished as circumstances may require.

Having thus described my invention what I claim as new and desire to secure by Letters Patent is,

1. The combination with a telegraph relay instrument of a closed sounding drum having integrally formed periphery and heads, a sounding horn connected with the periphery of said drum, a vibratory arm provided with contact bearings connected with the armature of said relay instrument and adapted to alternately communicate a vibratory movement to the respective heads of said drum with each vibratory movement of said armature.

2. The combination with a telegraph relay instrument of a closed sounding drum, a horn connected with said drum, a vibratory arm provided with contact bearings connected with the armature of said relay instrument and extending into the interior of said drum, adjustable means for limiting the vibratory movement of said vibratory arm, said bearings being adapted to alternately

communicate a vibratory movement to the respective heads of said drum with each vibratory movement of said armature.

3. The combination with a telegraph relay instrument of a sounding drum, a horn connected with the periphery of said drum, adjustable contact bearings centrally supported from the heads of said drum and a vibratory arm provided with contact bearings connected with the armature of said relay instrument, the bearings of said vibratory

arm being adapted to alternately contact with the adjustable contact bearings supported by said heads with each vibratory movement of said armature, all substantially as and for the purpose specified. 15

In testimony whereof I affix my signature in the presence of two witnesses.

ALFRED J. MEYER.
